DESIGN FOR A BROOCH

Louis Silverfield, San Francisco, Calif.

Application October 9, 1940, Serial No. 95,708

Term of patent 7 years

To all whom it may concern:

Be it known that I, Louis Silverfield, a citizen of the United States of America, residing at San Francisco, in the county of San Francisco and State of California, have invented a new, original, and ornamental Design for a Brooch, of which the following is a specification, reference being had to the accompanying drawing, forming a part thereof.

Fig. 1 is a perspective view of a brooch, showing my new design; and,

Fig. 2 is a similar view of the rear of the brooch.

I claim:

The ornamental design for a brooch, substantially as shown.

LOUIS SILVERFIELD.
